UNITED STATES PATENT OFFICE.

JAMES T. DAVENPORT, OF GALESBURG, ILLINOIS.

ADJUSTABLE PLOW AND SHOVEL.

Application filed February 28, 1927. Serial No. 171,636.

My invention relates to improvements in adjustable plows and shovels, and it consists in the combinations, constructions, and arrangements herein described and claimed.

- 5 An object of my invention is to provide an adjustable plow and shovel which has novel means for holding the shovel in adjusted position yet permitting the shovel to swing should it strike a stone or the like.
- 10 A further object of my invention is to provide a device of the type described in which the novel adjustment is positioned adjacent the shovel.

A further object of my invention is to provide a device of the type described in which the shovel is so shaped that when a plurality of shovels is used upon a cultivator, they will overlap.

A further object of my invention is to provide a device of the type described which will sever weeds or vines of any type, and will not make furrows as does the ordinary shovel.

A further object of my invention is to provide a device of the type described in which the shovel may be adjustably held in any desired position with respect to the surface of the ground.

Other objects and advantages will appear in the following specification, and the novel features of the invention will be particularly pointed out in the appended claims.

My invention is illustrated in the accompanying drawings, forming part of this application, in which

Figure 1 is a side elevation of the device as applied to a shank of a cultivator,

Figure 2 is a plan view of the device,

Figure 3 is a section along the line 3—3 of Figure 1, and

Figure 4 is a bottom plan view of a portion of the device.

In carrying out my invention, I provide a supporting member 1 which in actual use will be a shank of a cultivator, not shown.

45 A body portion 2 is provided with an opening 3 which is adapted to receive the supporting member 1. Lugs 4 are integral with the body portion and are adapted to be drawn together by a bolt 5 for removably securing the body portion to the supporting member.

The body portion 2 is provided with an integral flange or lip portion 6 having an arcuate-shaped groove 7 in its inner surface. A clamp 8 having an arcuate-shaped groove 9 within one side thereof is provided

with a tongue portion 10 which is receivable within a longitudinally extending groove 11 in the body portion 2.

A substantially triangular-shaped shovel 12 is rigidly secured to a bracket 13. The shovel 12 gradually curves upwardly from a point approximately the center thereof to the point 14 of the shovel, see Figure 1. The bracket 13 is provided with a head or ball-shaped member 15 which is provided with arcuate-shaped surfaces 16 and 17. The arcuate-shaped surface 16 is receivable within the arcuate-shaped groove 7. The clamp 8 is adapted to be disposed in place whereby the tongue 10 is receivable in the groove 11 and the arcuate-shaped surface 17 is receivable in the arcuate-shaped groove 9. The clamp 8 and the bracket 13 are adjustably secured to the body portion 2 by means of a bolt 18 which extends through openings in the clamp 8, the head 15, and the flange 6.

From the foregoing description of the various parts of the device, the operation thereof may be readily understood. In Figure 1, I have shown the device in the position in which it is best used. The dotted line A represents the surface of the ground. As the device is moved forward in the direction of the arrow B, it is obvious that the shovel 12 for its entire width is disposed beneath the ground and will sever all weeds or vines which happen to be in its path during the forward movement thereof. If the shovel 12 should strike a stone or other obstacle which could not be moved by the forward movement of the shovel, the friction between the arcuate-shaped surfaces 16 and 17 of the head or ball-shaped member 15 and the arcuate-shaped grooves 7 and 9 would be overcome, thus allowing the shovel to swing about the bolt 18 as a pivot. The shovel and bracket may readily be reset, i. e., moved into their normal positions by making loose the bolt 18.

The purpose of Figure 4 is to illustrate how the edges and point of the shovel 12 are kept polished by constant use. This also illustrates that the shovel moves in a substantially horizontal plane with respect to the surface of the ground. During this movement the weeds or the like may be more readily severed. Furthermore the shovel may be moved with less energy and more evenly in comparison with the ordinary type of shovel.

The adjustment adjacent the shovel makes it possible to move the shovel upwardly about

the bolt 18 when the device is not in use. The adjustment also obviates the need of pegs which are used with the ordinary type of cultivator shovel.

5 I claim:

1. A device of the type described comprising a support, a body portion having an elongated groove therein, means for removably securing said body portion to said support, a flange having an arcuate-shaped groove integral with said body portion, a clamp having an arcuate-shaped groove therein, a tongue portion integral with said clamp and receivable in the groove in said body portion, a bracket, a shovel rigidly secured to said bracket, a head portion integral with said bracket and having arcuate-shaped walls re-

ceivable in the arcuate-shaped grooves in said clamp and said flange, and means for adjustably securing said head portion between said clamp and said flange. 20

2. A device of the type described comprising a support, a body portion arranged to be secured to said support and having an arcuate-shaped groove therein, a shovel, a bracket secured to said shovel and having arcuate-shaped walls, one of which is adapted to be received in the arcuate-shaped groove of said body portion, a clamp having an arcuate-shaped groove adapted to receive the other of 25 said arcuate-shaped walls, and means for adjustably securing said bracket between said body portion and said clamp. 30

JAMES T. DAVENPORT.
